(57) **CLAIM**

The ornamental design for a transformer for electronic device, as shown and described.

DESCRIPTION

FIG. 1 is a perspective view of the top, front and right side of a transformer for electronic device showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof; and,

FIG. 7 is a left side view thereof.

1 Claim, 4 Drawing Sheets

FIG. 1

*FIG. 2**FIG. 3**FIG. 4**FIG. 5**FIG. 6**FIG. 7*
